UNITED STATES PATENT OFFICE.

ROBERT H. BLISS AND GRAYDON C. BLISS, OF EAST SYRACUSE, NEW YORK.

SASH.

Application filed May 23, 1921. Serial No. 471,747.

This invention relates to metallic window sash and particularly to such sash constructions comprising a stationary portion and a swinging transom or panel pivotally attached thereto and adapted to be opened for the purpose of ventilation.

In windows of this class having swinging panels it is essential that tight joints be had between the stationary portions and the panels when the panels are closed, so that no wind can blow or rain or snow penetrate between the edges of the panel and the edges of the stationary portion. It has been suggested, therefore, to provide a double metallic contact, or two separate joints, between the stationary and swinging portions entirely around the margin of the panel, the theory being that such wind, rain or snow as might penetrate the first joint would be intercepted by the second. In such constructions the joints have been separated by an air chamber. Due to the slight unevenness of the metallic members of which the sash is constructed, it has been found in practice extremely difficult to provide a thoroughly weatherproof fit between the stationary portion of the sash and the swinging portion, even with such double metallic contact between these portions.

A further defect of such prior constructions resides in the tendency of rain or snow to penetrate through the first joint of the weathering construction and to gather in the chamber between the two joints thereby causing the metallic sash members to rust, finally become unsightly and eventually resulting in the destruction of the sash.

The object of the present invention is to provide a sash construction in which the joint between the stationary and swinging portions has the usual double contact or two parallel joints, but in which there is no air space between the contacting edges, and in which one contact is made between two metallic members and the other contact is made between a single metallic member and an insert of softer material which will conform to the shape of the metal member, to insure a tight joint. No room is left, therefore, in which moisture can condense and the joint is made so tight that all leakage is prevented.

One embodiment of the invention will be

disclosed in the following description when taken with the drawings accompanying the same.

In the drawings:

Fig. 1 is an elevation of a sash construction embodying the improvements;

Fig. 2 is a section on line 2-2 of Figure 1;

Fig. 3 is a section on line 3-3 of Figure 1;

Fig. 4 is a section on line 4-4 of Figure 1;

Fig. 5 is a section on line 5-5 of Figure 1;

Fig. 6 is a rear view of portion of the lower member of the swinging panel showing its securing latch and supporting bar;

Fig. 7 is a section through the joint between the stationary and swinging portions, but showing a modified form of filler member.

Both stationary and swinging portions of the sash are built up of T bars or munnions 10 of well known type and are jointed together in any well known manner, but preferably according to the method described by us in our copending application Serial No. 348,367 filed December 30, 1919. The swinging transom or panel 11 may be of any size and pivoted in any desired manner, but in the drawings it is shown as pivoted at 12 and 13 so that it swings about a horizontal central axis. The bars 10 of the stationary portion which define the margin of the central opening for the transom and the outer frame bars of the transom lie parallel, as shown clearly in Figures 2, 3 and 4. In opening the panel its lower end is swung outwardly and its upper end inwardly, it being understood that the outside of the window is that side on which the heads of T bars 10 are located.

Double contact or weathering is realized completely around the joint between the transom and stationary frame by employing the angle bars 14 and filler pieces 15.

In the upper half of the sash the angle bars are secured to the webs of the marginal T bars of the transom and extend laterally to contact with the rear edges of the webs of the stationary frame. In the lower half of the sash the positions of the angle bars

are reversed, that is, they are secured to the webs of the marginal T bars of the frame and extend in rear of, so as to contact with the rear edges of the webs of the marginal 5 T bars of the transom. The filler members 15 are secured in each case by any suitable means, to that T bar to which the adjacent angle bar is secured, that is, at any point, both filler member and angle bar are secured 10 to the same T bar.

The fillers are of such size as to practically occupy all of the space between the flange of the angle bar and the heads of the T bars, and the front faces of the fillers are 15 adapted to contact with the rear faces of the flanges of those adjacent T bars to which they are relatively movable. A double contact therefore results at each point around the sash, the first joint being between the 20 filler and the rear face of the flange of the adjacent T bar and the rear joint being between the angle bar and the rear edge of the web of the same T bar. The fillers may be of 25 wood or any other suitable material which is softer than the metallic T bars such as for instance, strips of asbestos fiber. Where wood is used we may employ a thin weather strip 16 of metal or harder material than wood, as shown in Figure 7 and may use if 30 desired, an additional weather strip 16', secured to that T bar which does not have the filler member secured thereto. In use the softer filler soon adapts itself to the irregularities of the metal T bar with which it 35 contacts and provides a closer joint than could be realized with metal to metal contact. The filler practically prevents condensation between the joints, in addition to excluding rain and snow, and all tendency of the sash 40 to rust in this space is, therefore, avoided.

The sash is retained in closed position by means of a spring latch 17 adapted to snap over the upper edge of the angle bar 14 which is secured to the stationary frame at 45 the bottom of the transom opening. This latch is pivoted at 18 and a strong spring 19 normally keeps it in locking position. The latch has an upwardly extending portion 17' which has an aperture 20 therein. 50 The angular bar 21 has a ring at its end which extends through the aperture 20 so that the latch 17 and bar 21 are pivotally connected together. Bar 21 has a series of notches 22, each of which is adapted to fit 55 over the upper edge of angle bar 14 and to hold the transom in any desired position relatively to the stationary portion of the frame, as for instance in the position shown in dotted lines in Figure 5. When in closed 60 position bar 21 is turned so as to be parallel to the angle bar 14 and its end is held between the bar 14 and a cleat 23 secured thereto. The window can not be opened

without lifting bar 21 and it, therefore, constitutes an additional locking means. 65

From the above description of the invention its advantages will be realized by those skilled in the art, and it will also be apparent that numerous changes may be made in the design and arrangement of the component 70 parts without departing from its scope and intent.

Having thus described the invention what is claimed as new and desired to be secured by Letters Patent is:

1. In a metallic window construction, in combination, a stationary portion and a swinging portion, said portions having marginal metallic bars which lie slightly spaced apart and substantially parallel when the window is closed, and means for closing the gap between the said spaced parallel bars including a metallic member and a fiber member, both of said members being rigid with one of said bars and extending toward 80 the other to make contact therewith along spaced parallel lines, and the fiber member substantially filling the space between the marginal bars when the window is closed, 85 for the purpose set forth. 90

2. In a metallic window construction, in combination, a stationary portion and a swinging portion, said portions having marginal metallic T-bars which lie slightly spaced apart with their webs substantially 95 parallel, when the window is closed, and means for closing the gap between the said spaced parallel T-bars including a metallic member and a fiber member, both members being rigid with one of said bars and extending toward the other to make contact therewith along spaced parallel lines, for the purpose set forth. 100

3. In a metallic window construction, in combination, a stationary portion and a swinging portion, said portions having marginal metallic T-bars which lie slightly spaced apart with webs substantially parallel when the window is closed, and means for closing the gap between the said spaced 105 parallel T-bars including a metallic angle bar and a wood strip, both secured to one of said T-bars and extending toward the other to make contact therewith, the flange of said angle bar making contact with the rear edge of the T-bar to which it is not secured, and the wood strip making contact with the rear face of the head of the T-bar to which it is not secured, the lines of contact specified being substantially parallel, for 110 115 the purpose set forth. 120

In testimony whereof we hereunto affix our signatures.
